MULTIPLE BLADE SCREW DRIVER

Raymond P. Lavietes, Shelton, Conn., assignor to
Shelton Plane and Tool Manufacturing Company, Shelton, Conn., a corporation of Connecticut

Application July 15, 1949, Serial No. 104,999

3 Claims. (Cl. 145—64)

1

This invention relates to an improved multiple blade screw driver, and has for its main object a tool provided with several different sized screw driver blades conveniently contained within the tool, offering quick and easy selection of the desired blade and protection against detachment or loss of one or more blades.

In some of the old devices separate blades are stored in a hollow handle portion having a detachable closure cap. In other old devices smaller size screw drivers telescope within the hollow handle portion of successively larger and separate screw drivers. In the first mentioned of the old devices the hollow handle portion must be first opened by removing a screw cap or other closure, the desired blade removed and attached to the handle in operating position, and the screw cap or other closure returned to close the hollow handle chamber. The blades are not permanently connected with the handle portion and may easily become lost. The cap or other closure means may likewise become easily lost or misplaced.

In my invention all the parts are protected against detachment and loss. My invention offers a simple, quick and effective device to permit selection of the desired blade and almost instant positioning of the selected blade in operating position without danger of loss of any blades or closure members.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a side view of the device;

Figure 2 is an end view of Fig. 1;

Fig. 3 is another side view at right angles to the view in Fig. 1 and partly in section, and also showing a blade extended in position for use;

Fig. 4 is a sectional view at line 4—4 of Fig. 3;

Fig. 5 is similar to Fig. 1 with blade holder and blades drawn out;

Fig. 6 is another view of the blade holder at right angles to Fig. 5, a portion of the handle member in section and the means for limiting total withdrawal of the blade holder from the handle;

Fig. 7 is an end view of Fig. 6, and

Fig. 8 is a top plan view of the blades shifted to various positions within the blade holder.

In the preferred embodiment as illustrated in the drawings, a substantially circular knob 10, flat on two opposing sides 11, is provided with a longitudinally extending neck 12 and a short

2

shank 13. The shank is made to fit telescopically within one end of a longitudinal cylindrical chamber 14 of a longitudinal tubular handle member 15. Suitable means is provided for securing the member 10 to handle member 15. In the present device a hole 16 is provided in the shank and opposing holes to line up with this hole are provided in the tubular handle member so that a retaining pin or rivet 17 through said holes retains the circular knob 10 in rigid connection with the handle member 15 after final assembly, as hereafter more fully explained.

The tubular opening of the handle member 15 at the end opposite the circular knob is smaller than the remainder of the chamber opening and flat on opposite sides 14a so as to provide a pair of shoulders 18 within the handle member. This opening is not entirely circular. In the illustrated and preferred embodiment, the opening has two opposing flat walls, and two opposing circular walls, thereby preventing the blade holder hereafter described from turning freely in the handle.

A blade holder or frame generally designated 19 comprises a pair of spaced longitudinal side members 19a and 19b flat on the interior surface and rounded on their exterior surfaces to slidably engage the interior of the tubular handle member. Spacing of members 19a and 19b is accomplished by a screw stud 20 within a spacing collar 20a at one end, and a plurality of screw driver blades 21 pivotally mounted at the other end by pivot screw 22.

The screw driver blades are of varying sizes for use with various size screw heads and of proper length to permit full rotation around pivot 22 yet short enough to clear the spacer collar 20a. The aggregate thickness of all the blades should be approximately equal to the length of the spacer collar 20a.

A few turns of spring wire are coiled around the periphery of the spacer collar to form a coil spring 23 with both free ends terminating in outwardly turned hooks 23a, said free ends opposing each other. These hooked ends tend to separate under action of the spring coil so as to frictionally engage the side walls of the chamber or bore 14 to retain the frame and the blades in the handle when not in use.

The blade holder or frame generally designated 19, comprising the pivotally mounted screw driver blades 21 within its opposing longitudinal members 19a and 19b, the spacer collar 20a, stud 20 and the coil spring 23, is inserted within the chamber 14 at its widest opening, or that is the end in which the knob 10 is mounted before this knob is attached, and with the end carrying the pivot 22 entering the chamber first. The free ends of the coil spring are adapted to exert an outward spring action and therefore

friction against the wall of the chamber 14 and are compressed together to allow insertion into the tube chamber. The blade holder being semi-round on two opposing sides and flat on its other sides is fitted through the smaller end opening at the outer end of the tubular chamber. The shank 13 of the knob 10 is then telescoped into position within the tubular handle member 15 at its larger end opening, the opposing holes in the tubular member and the corresponding hole 15 in the knob shank are aligned and the pin or rivet 17 run through to rigidly fasten the knob to the tubular handle member.

The spring ends 23a act as a stop against internal shoulders 18 to limit outward travel of the blade holder and prevent it from falling out, or otherwise becoming detached from the handle member.

In the preferred embodiment shown in the drawing, I have provided the outer peripheral surface of the hollow handle member 15 with a knurled surface 15a for better gripping, although any similarly roughened surface may be provided.

In operation, to expose a blade for use the blade holder is slidably withdrawn from the hollow handle member to its limit of slide travel, as in Fig. 6, the desired blade is pivoted outwardly on pivot 22 so that the screw head engaging portion of the desired blade is in operating position, the remainder of the blades are pivotally returned within the blade holder between the longitudinal members 19a and 19b so that the screw head engaging portions of the undesired blades face the handle member. The whole frame 19 with the blades is then slid back into the handle to the position of Fig. 3. In this position the inner end 21b of the blade 21a, which is turned with its bit end 21c exposed for use, is located between the flats 14a of the opening in the outer end of the handle and cooperate therewith to hold the blade rigidly in this position and prevent it from swinging on its pivot 21 when in use.

Thus my invention provides a multiple blade screw driver offering a choice of several size blades, any of which may be easily and quickly selected and instantly turned to operating position. All of the component parts are interconnected, thus preventing misplacement or loss. There is no closure cap to become misplaced or lost. The operation required in some of the old devices, requiring the fitting of the shank of a blade into a socket, chuck, collet or other holding means, is entirely eliminated. My device also offers the advantage of being convenient to carry as a pocket tool.

Having thus set forth the nature of my invention, I claim:

1. A blade tool comprising a blade holder including a pair of spaced and opposed longitudinal members held at one end by a spacing collar and stud transversely holding the longitudinal members in spaced position, a tool blade pivotally mounted between the other ends of the longitudinal members, the interior surfaces of the longitudinal members being substantially flat and their exterior surfaces being rounded, a tubular handle member having a longitudinal passage including at one end of the member an opening comprising two opposing flat wall surfaces and two opposing convex wall surfaces, the peripheral interior surface of said handle member slidably engaging the rounded exterior surfaces of the blade holder with the edges of the members of the holder engaging the flat surfaces

of the opening to prevent turning of the holder in the handle member, a pair of opposing shoulders protruding from the interior of the handle member near its first mentioned end opening, a substantially U-shaped spring retaining member including an intermediate coil wound around the spacing collar, its free ends formed with outwardly extending hooks having frictional engagement with the internal walls of the handle member and positioned to cooperate with the shoulders to limit outward movement of the blade holder, a hand knob at the other end of the handle member, the blade holder being slidably guided within the handle member so that it may be drawn out to the stop position allowed by the engagement of the hooks with said shoulders, so that the blade may be turned on its pivot to operating position and the blade holder then slid back into the handle and prevented from turning within the handle.

2. A blade tool comprising a tubular handle member provided with a longitudinal passage opening through its opposite ends, the opening at one end being noncircular and smaller than the passage providing stop shoulders at the inner side of this opening, a blade holder comprising a pair of spaced longitudinal members slidably fitting within the handle member and slidably engaging the opening longitudinally, said holder being noncircular and held against rotation by said opening, a tool blade pivotally mounted within the blade holder by a pivot stud running transversely through the blade holder and the blade, said holder being slideable longitudinally in the handle member between a retracted position in said member and an extended position to permit turning of the blade in the holder, and a spring carried by the blade holder including arms tending to move outwardly to frictionally engage the side surfaces of said passage and in position to engage the shoulders to retain the blade holder against complete withdrawal from the handle member.

3. A blade tool comprising a tubular handle member provided with a longitudinal chamber, a blade holder slidably fitted within the handle, a tool blade pivotally mounted within the blade holder so that its position may be reversed in the holder, said member being provided with a noncircular opening through one end leading to said chamber and smaller than the chamber so as to provide a pair of opposed shoulders protruding into the handle chamber from the internal wall of the handle near said end, stop means attached to the blade holder comprising a spring including arms tending to move laterally to frictionally engage the walls of the chamber and arranged to co-act with the shoulders to prevent complete withdrawal of the blade holder from the handle, said holder being slideable between a position in the handle and an exposed position to permit reversal of the blade, and said blade holder being noncircular and located in the opening so as to be held thereby against rotation of the blade holder within the handle.
